DESIGN FOR A LIGHTING FIXTURE BOWL OR SIMILAR ARTICLE

Thomas W. Rolph, Newark, Ohio, and Henry L. Logan, New Rochelle, N. Y., assignors to Holophane Company, Inc., New York, N. Y., a corporation of Delaware

Application August 18, 1938, Serial No. 79,426

Term of patent 14 years

To all whom it may concern:

Be it known that we, Thomas W. Rolph and Henry L. Logan, citizens of the United States of America and residents, respectively, of Newark, in the county of Licking and State of Ohio; and New Rochelle, in the county of Westchester and State of New York, have invented a new, original, and ornamental Design for a Lighting Fixture Bowl or Similar Article, of which the following is a specification, reference being had to the accompanying drawing, forming a part thereof.

Fig. 1 is a perspective view of the lighting fixture bowl, showing our new design.

Fig. 2 is a view partly in section and partly in elevation of the lighting fixture bowl.

We claim:

The ornamental design for a lighting fixture bowl or similar article, as shown.

THOMAS W. ROLPH.
